UNITED STATES PATENT OFFICE.

GIULIO MERONI, OF MILAN, ITALY.

WOODEN FURNITURE HAVING CURVED OR SIMILARLY SHAPED SURFACES.

Application filed February 7, 1923, Serial No. 617,607. Renewed July 20, 1925.

To all whom it may concern:

Be it known that I, GIULIO MERONI, subject of the Kingdom of Italy, residing at Milan, Via Torino 45, have invented certain new and useful Improvements in Wooden Furniture having Curved or Similarly Shaped Surfaces, of which the following is a specification.

The present invention relates to improvements in that class of inventions known as furniture and more particularly embraces improved wooden furniture having curved or similarly shaped surfaces.

The object of the invention resides in the provision of an article of furniture comprising a wooden casing composed of a plurality of laminated sheets, such as veneer which are glued together crosswise of the grains of the adjacent sheets and shaped corresponding to the outer surface of the inner mould by pressing the outer mould thereagainst and simultaneously heating the sheets, the openings for the drawers, doors, etc. being subsequently cut out in a desired manner, for example, by sawing.

This type of construction makes it possible to produce sets of solid and durable furniture.

Other objects as well as the nature, characteristic features and scope of the invention will be more readily apparent from the following description taken in connection with the accompanying drawings and pointed out in the claims forming a part of this specification.

The invention is clearly illustrated in the accompanying drawings, in which:—

Fig. 1 is a horizontal section taken through the inner mould for the wooden wall forming the outer casing of the article and the counter-mould on which pressure is exerted,

Fig. 2 is a front elevational view of the improved article,

Fig. 3 is a vertical section through the line 3—3 of Fig. 1, and

Fig. 4 is an enlarged transverse sectional detail.

Referring now, more particularly, to the drawings there is provided a continuous

wall 1 consisting preferably of a plurality of wooden sheets glued together in juxtaposed relation and with the grains of one sheet arranged crosswise to the grains of the adjacent sheet, the composite sheet being arranged about the mould 3 and subjected to heat and pressure by the blocks 2, the latter constituting the counter-mould and having curved surfaces corresponding to the curved outer surface of the inner mould so that the completed wall will be curved at predetermined positions as desired. Subsequently the moulds are removed in any desired manner and the curved front wall of the casing has portions 4 cut out therefrom as by sawing so as to leave openings 4' for the drawers and doors, etc. and these portions 4 are subsequently used by being applied to the front faces of the drawers so as to enhance the appearance of the completed article.

It is apparent that this method of operation may be applied for the production of other articles of furniture without leaving the scope of the invention. For example, as indicated in Fig. 4, the corners provided at the rear wall *o*, *p*, of the article may be formed so that the composite sheet is subdivided into two parts *m*, *n*, one part *m* forming a right angle with the main wall *o* and the space formed between the other portion *n* being filled out with a wood bar or the like *h*.

It is believed in view of the foregoing that a further detailed description of the drawing is entirely unnecessary. Likewise it is believed that the advantages of the invention will be readily apparent.

Having thus fully described the invention what is claimed as new and desired to be secured by Letters Patent is:—

1. The method of forming an improved article of furniture consisting in arranging composite sheets of veneer about a mould to form a casing having a continuous wall and heating and pressing the sheets so as to ensure of the article retaining the moulded form, and finally removing portions of the wall so as to provide openings.

2. An article of furniture comprising a

casing formed of composite layers of wood glued together so that the grains of wood of one layer will lie crosswise to the grains of wood of the adjacent layer forming a substantially continuous wall having a curved front face, portions cut away from the front face of the wall so as to provide

openings for drawers, doors, etc., and subsequently forming the facing of the drawers, doors, etc. so as to enhance the appearance 10 of the article.

In testimony whereof I affix my signature.

GIULIO MERONI.
